(57) **ABSTRACT**

A new *Anthurium* plant named 'ANTHAMYO' particularly distinguished by having wavy, shiny, strongly blistered, bright red, cordate and very durable spathes that retain the original color for a very long period of time, dark green and deltoid, durable leaves, white spadices with yellow tips, early and rich flowering continuously throughout the year, and a plant height of 33.0 cm to 38.0 cm is disclosed.

3 Drawing Sheets

1

Genus and species: *Anthurium andraeanum* L.
Variety denomination: 'ANTHAMYO'.

BACKGROUND OF THE NEW PLANT

The present invention comprises a new and distinct variety of *Anthurium*, botanically known as *Anthurium andraeanum* L., and hereinafter referred to by the variety name 'ANTHAMYO'. The new *Anthurium* plant is a product of a planned breeding program conducted by the inventor in Bleiswijk, the Netherlands. The objective of this breeding program was to create a new 33.0 cm to 38.0 cm height plant with wavy, shiny and strongly blistered, bright red, cordate and very durable spathes.

The new variety originated from a cross-pollination made in April 2009 in Bleiswijk, The Netherlands. The female parent was a red *Anthurium* pot plant designated '8477-07' (unpatented), and the male parent was a red *Anthurium* pot plant designated '15376-05' (unpatented).

A single plant was selected from the progeny of the stated cross in December 2010. Asexual reproduction of the new variety by tissue culture in 2014 in Bleiswijk, The Netherlands, has demonstrated that the new variety reproduces true to type with all of the characteristics, as herein described, firmly fixed and retained through successive generations.

Plant Breeder's Rights for this variety have been applied for in the European Union on Nov. 27, 2017. 'ANTHAMYO' has not been made publicly available or sold anywhere in the world more than one year prior to the effective filing date of this application.

SUMMARY OF THE INVENTION

The following are the most outstanding and distinguishing characteristics of this new variety when grown under normal horticultural practices in Bleiswijk, The Netherlands:

2

- 1) Wavy, shiny and strongly blistered, bright red, cordate spathes;
- 2) White spadices with yellow tips; and
- 3) Green, deltoid leaves.

DESCRIPTION OF THE PHOTOGRAPHS

This new *Anthurium* plant is illustrated by the accompanying photographs which show the overall plant habit including blooms and foliage of the plant; the colors shown are as true as can be reasonably obtained by conventional photographic procedures. The photographs are of a 34-week old plant grown in a greenhouse in Bleiswijk, The Netherlands, in November 2018. Colors in the photographs may differ from the color values cited in the detailed botanical description, which accurately describe the actual colors of the new variety.

FIG. 1 shows the overall plant habit, including blooms and foliage.

FIG. 2 shows a close-up of the mature spathe.

FIG. 3 shows a close-up of the upper leaf blade surface.

DESCRIPTION OF THE NEW VARIETY

The following detailed description sets forth the distinctive characteristics of 'ANTHAMYO'. The data which define these characteristics were collected from asexual reproductions carried out in Bleiswijk, The Netherlands. The plant history was taken on 34-week old plants which were planted from tissue culture in 12 centimeter (diameter) pots and grown in a glass greenhouse between 19° C. and 24° C. Observations were made in November 2018. Color readings were taken under 5000 lux natural light in the greenhouse. Color references are primarily to The R.H.S. Colour Chart of The Royal Horticultural Society of London (R.H.S.) (2015).

DETAILED BOTANICAL DESCRIPTION

Classification:

Family.—Araceae.

Botanical.—*Anthurium andraeanum* L.

<i>Common name.</i> — <i>Anthurium</i> .	<i>Shape.</i> —Cordate.
<i>Denomination.</i> —‘ANTHAMYO’.	<i>Apex.</i> —Abruptly acuminate.
<i>Parentage:</i>	<i>Base.</i> —Cordate.
<i>Female parent.</i> — <i>Anthurium</i> plant ‘8477-07’ (un-patented).	<i>Texture.</i> —Shiny and strongly blistered.
<i>Male parent.</i> — <i>Anthurium</i> plant ‘15376-05’ (un-patented).	<i>Margin.</i> —Undulated.
<i>Plant:</i>	<i>Size.</i> —Length: 11.0 cm to 12.0 cm. Width: 9.5 cm to 10.5 cm.
<i>Propagation.</i> —Tissue culture.	<i>Lobes.</i> —Present. Arrangement: The spathe has two lobes extending past the peduncle. The lobes are non-touching. Length: 2.0 cm to 2.5 cm. Width: 4.0 cm to 5.0 cm.
<i>Root description.</i> —Fleshy, light yellow with yellow- ¹⁰ ish-pink shade colored roots with small hairy lateral roots having yellow colored root tips.	<i>Color.</i> —Just fully open: Upper surface: RHS 45B. Lower surface: RHS 45D. This bright red color remains for a very long period, at least more than 30 weeks after opening.
<i>Time to produce a finished flowering plant.</i> —32 to 36 weeks after planting in a 12 cm (diameter) pot.	<i>Peduncle:</i>
<i>Growth habit.</i> —Upright.	<i>Shape.</i> —Erect.
<i>Height (measured from soil, including inflorescence):</i> —33.0 cm to 38.0 cm.	<i>Cross-section.</i> —Round.
<i>Width (measured from leaf tips):</i> —42.0 cm to 47.0 cm.	<i>Length.</i> —26.0 cm to 31.0 cm.
<i>Leaves:</i>	<i>Diameter.</i> —0.3 cm to 0.4 cm.
<i>Immature leaves.</i> —Length: 15.0 cm to 17.0 cm. Width: 10.0 cm to 11.0 cm. Color: Upper surface: RHS 146A. Lower surface: RHS 146B. Texture (both upper and lower surfaces): Shiny, soft and smooth.	<i>Color.</i> —RHS 144C.
<i>Mature leaves.</i> —Length (fully expanded): 17.0 cm to 19.0 cm. Width: 12.0 cm to 13.0 cm. Shape: Deltoid.	<i>Flowering time:</i>
<i>Apex:</i> Acuminate. <i>Base:</i> Cordate. Leaf blade angle with the petiole: Between 110 degrees and 130 degrees. Leaf margin: Entire. Color: Upper surface: RHS 147A. Lower surface: RHS 146B. Texture (both upper and lower surfaces): Shiny, leathery and thick. Venation: Pinnate veining; the mid-vein and primary veins (the veins that radiate out from the junction of petiole and leaf) protrude at the underside of the leaf blade. Venation color: Upper surface: RHS 144A. Lower surface: RHS 144B.	<i>General.</i> —One small, rooted, untreated tissue culture plant of 8.0 cm tall will flower, depending on the season, after 32 to 36 weeks and 9 to 10 blossoms appear. More blossoms appear after some additional weeks so that a full flowering and commercial plant will have 11 to 12 bright red spathes. Smaller blossoms may occur on immature plants.
<i>Lobes.</i> —Present. Arrangement: Leaf blade has two lobes extending past the petiole. The lobes are non-touching. Length of lobes of mature leaf blades: 2.0 cm to 3.0 cm. Width of lobes of mature leaf blades: 5.0 cm to 6.0 cm. Distance from petiole/leaf junction to highest point on lobes of mature leaf: 4.0 cm to 5.0 cm.	<i>Spadix:</i>
<i>Petiole.</i> —Cross-section: Round. Diameter: 0.3 cm to 0.4 cm. Length: 21.0 cm to 24.0 cm for a mature leaf size. Color: Mature leaf: RHS 144A. Immature leaf: RHS 144B. Cataphyll color surrounding the petiole: Outside: RHS 181B/C with green middle vein (RHS 144C) toward tip. Inside: RHS 181D.	<i>Size.</i> —Length: 3.0 cm to 3.5 cm (depending on flower size). Width (at apex): 0.5 cm to 0.6 cm. Width (at base): 0.6 cm to 0.7 cm.
<i>Geniculum.</i> —Length: 2.0 cm to 2.5 cm. Width: 0.4 cm to 0.5 cm. Color: RHS 144B.	<i>Shape.</i> —Columnar.
<i>Inflorescence:</i>	<i>Angle from spadix tip to peduncle.</i> —160 degrees to 180 degrees.
<i>Arrangement.</i> —Single.	<i>Texture.</i> —When the spathe is unfurling the spadix is smooth. When the spadix matures, small stigmata protrude. The stigmata are evenly distributed around the spadix. The spadix matures from base to top, slowly giving the spadix a somewhat rough appearance.
<i>Flowering habit (length of flowering season).</i> —Continuous.	<i>Color.</i> —Immature: RHS 13A. Mature: RHS 155B. Ages to: RHS N144A.
<i>Number of inflorescences per plant.</i> —10 to 12.	<i>Flowers:</i>
<i>Fragrance.</i> —Absent.	<i>Quantity per spadix.</i> —80 to 120.
<i>Longevity of inflorescence on plant.</i> —Over a year.	<i>Spadix flower arrangement.</i> —Bisexual, rounded in cross-section.
<i>Spathes:</i>	<i>Shape.</i> —Rounded.
<i>Buds.</i> —The spathe is tightly rolled around the spadix and extrudes from the peduncle sheath. After the spathe is fully open, the peduncle elongates some extra centimeters.	<i>Size.</i> —Length: 0.05 cm to 0.10 cm. Diameter (maximum): 0.10 cm.
<i>Arrangement.</i> —Spathe angle with the peduncle is between 95 degrees and 110 degrees; the spathe stands on a wiry peduncle about 3.0 cm to 6.0 cm above the foliage.	<i>Color.</i> —RHS 155D.
	<i>Reproductive organs:</i>
	<i>Stamens.</i> —Not visible.
	<i>Pollen amount.</i> —Absent.
	<i>Pistil.</i> —Quantity: 80 to 120. Length: Less than 0.01 cm. Color: RHS 155D.
	<i>Style.</i> —Not observed to date.
	<i>Sigma.</i> —Shape: Ovoid. Diameter: Less than 0.01 cm. Color: RHS 155D.
	<i>Ovary.</i> —Rarely visible.
	<i>Ovary color.</i> —Not measured.
	<i>Fruit and seed set:</i> None observed to date.
	COMPARISON WITH PARENTAL AND SIMILAR COMMERCIAL VARIETIES
	‘ANTHAMYO’ differs from the female parent plant ‘8477-07’ (unpatented) in that ‘ANTHAMYO’ has medium-

sized spadices, whereas '8477-07' has small spadices. Additionally, 'ANTHAMYO' has wider spathes and taller plants than '8477-07'.

The male parent plant of 'ANTHAMYO', cultivar '15376-05' (unpatented), is no longer in existence, so a 5 meaningful comparison cannot be made.

'ANTHAMYO' differs from similar commercial variety 'ANTHDUNDAL' (U.S. Plant Pat. No. 27,287) in that 'ANTHAMYO' has strongly blistered spathes that are wavy in cross section, whereas 'ANTHDUNDAL' has slightly 10 blistered spathes that are flat in cross section. Additionally, 'ANTHAMYO' has longer spathes and taller plants than 'ANTHDUNDAL'.

'ANTHAMYO' differs from similar commercial variety 'ANTHERBI' (U.S. Plant Pat. No. 28,241) in that 'ANTHAMYO' has cordate, strongly blistered spathes that are wavy in cross section, whereas 'ANTHERBI' has orbicular-cordate, blistered spathes that are flat in cross section. Additionally, 'ANTHAMYO' has longer spathes than 'ANTHERBI'.

I claim:

1. A new and distinct variety of *Anthurium* plant named 'ANTHAMYO', substantially as illustrated and described herein.
